ATTORNEY.

UNITED STATES PATENT OFFICE.

ARTHUR A. MERRITT, OF PROVIDENCE, RHODE ISLAND, ASSIGNOR TO WILLCOX & GIBBS SEWING MACHINE CO., OF NEW YORK, N. Y., A CORPORATION OF NEW YORK.

THREAD-TENSIONING MEANS FOR SEWING MACHINES.

Application filed February 10, 1921. Serial No. 443,932.

To all whom it may concern:

Be it known that I, ARTHUR A. MERRITT, a citizen of the United States, and a resident of Providence, Rhode Island, have invented new and useful Improvements in Thread-Tensioning Means for Sewing Machines, which invention is fully set forth in the following specification.

This invention relates to thread-tensioning means for sewing machines. One object is the provision of practicable and efficient adjustable thread-tensioning means whereby any desired tension may be imposed upon the thread according to conditions encountered. A further object is the provision of thread-tensioning means for a plurality of threads adapted to be simultaneously thrown into and out of operation as to all of said threads collectively and adjustable to individually determine the tension for each thread irrespective of the tension for other threads. A further object is the provision of such means in which the collective releasing and applying of the tension upon the plurality of threads does not disturb the individual tension adjustment for each thread.

Though designed especially for use in what are known commercially as the Willcox & Gibbs Sewing Machine Company's "Flatlock" machine, shown for example in patent to me No. 1,041,652, dated October 15, 1912, and "Feldlock" machine of patent to me No. 1,253,507, dated January 15, 1918, the thread-tensioning means of this invention may be used in other types of sewing machines and especially wherever it is desired to individually, or separately, tension threads under conditions such as or similar to those hereinafter set forth. At the left hand end of Fig. 49 and in Fig. 52 (Sheets 23 and 24) of the aforesaid Patent 1,041,652 there are shown four pairs of tension disks between which four needle threads pass, and another pair of tension disks between which a cross-thread passes, all of said disks for the needle threads being pressed together by a common spring whereby the tension is approximately equalized upon the four needle threads. The lifting of the presser-foot automatically actuates an arm (687 in Fig. 49) which releases or throws the tension means out of action upon all the threads simultaneously and maintains that condition until the

presser-foot is again lowered. Adjustment of the tension for the four needle threads in that structure is effected by adjustment of the tension of the single spring common to the four sets of disks for the four needle threads. That is, there is a tension adjustment common to all four needle threads with no provision for individually or separately adjusting the tension for each thread irrespective of the tension of the others. By the means of the present invention there is an individual or separate tension adjustment for each thread with means for simultaneously releasing and restoring the tension upon the plurality of threads without affecting the tension adjustment for each.

The aforesaid and other objects are attained by the present invention and by what is now believed to be the preferred embodiment thereof illustrated in the accompanying drawing, wherein—

Fig. 1 is a front elevation with the machine casing or frame in section;

Fig. 2 is a vertical transverse section 80 through the thread-tensioning means shown in Fig. 1;

Fig. 3 is a front elevation of parts of the thread-tensioning means;

Fig. 4 is a sectional view on line 4—4 of Fig. 2; and

Fig. 5 is a detail view of one of the parts.

In Fig. 1 there is shown at 10 a fragment of the top wall of the hollow bridge of the frame of a sewing machine such as shown 90 in the aforesaid Patent 1,041,652, and similarly at 11 there is shown a fragment of the wall of a hollow standard at one end of said machine frame. A bracket or frame, upon which the thread-tensioning means are 95 mounted, as presently described, comprises a base section or plate 12, an upright section or wall 13, and an end-plate or wall 14. Said base 12 seats against the top of wall 10 and is secured thereto by screws 15, 100 while end-plate 14 fits over and closes an opening in wall 11, as shown in Fig. 1. A horizontally disposed bar 16 is longitudinally movable in a bearing opening through base-plate 12 and at its left hand end carries an upright arm 17 connected at its upper end to the end of a rod 18 longitudinally movable in a horizontal bearing opening extending the entire length of upright wall 13. A spring 19 surrounding bar 16 110

bears at one end against plate 14 and at its other end against the hub of arm 17 around bar 16, the spring thus tending to move said bar, its arm 17 and rod 18, to the left in Fig. 1, such movement being limited by a stop pin 20 through bar 16 adapted to contact the end of base-plate 12. 21 is an up-standing swinging arm automatically actuated by the lifting and lowering of the 10 presser-foot for manipulation of the work under the latter. The beveled surface at the upper end of arm 21 actuates the end of bar 16 to move the same and rod 18 toward the right in Fig. 1 against the tension of spring 19 when the presser-foot is 15 lifted by its lifting means.

The upright wall 13 is recessed at 22, said recess intercepting the bearing opening for rod 18 and exposing that portion of said rod 20 which traverses said recess, as clearly shown. A presser-plate or anvil 23 has an upstanding extension positioned between two lugs 24, 24 on plate 13 at opposite edges respectively of the recess 22. A pivot pin 25 25 through the lugs 24 and the extension of presser-plate or anvil 23, hinges the latter to the bracket or frame of the thread-tensioning means. A lug 26 on the underside of presser-plate 23 projects into recess 22 of 30 wall 13 and contacts one or the other of two flattened surfaces 27, 28 of rod 18, said surfaces being at different elevations with respect to each other and the axis of the rod with an intervening flattened inclined surface 29.

The structure as illustrated is adapted to accommodate five threads, the four needle threads *a*, *b*, *c* and *d*, and cross thread *e*. Hence, five flat or blade springs 30 are 40 shown, each adapted at its free end to press one of the threads against the presser-plate 23 in tensioning said thread. Since these springs and the associated supporting and adjusting means for each spring are all alike, a description as to one will suffice for all. As clearly shown in longitudinal section, spring 30 is bent near its middle forming it into two approximately parallel offset sections, the lower of said section at the free 45 end of the spring bearing against presser-plate 23 and being slightly upturned at its free extremity. At its upper extension the spring is secured by a screw 31 to the underside of an angle-arm or bracket piece 32 which is in turn secured to the upper edge of wall 13 by a screw 33. An elongated thread-eyelet or tubular thread guide 34 projects through angle-arm 32. A tension adjusting screw 35 is threaded through the free end of 50 angle-arm 32, bears its inner end against blade-spring 30, and at its outer end has a milled-head to facilitate gripping with the fingers in turning the screw for adjustment. The screw is split longitudinally to give a 55 spreading spring against the threaded wall

of its opening and thereby maintain the position to which it is adjusted. 36 are thread guiding hooks, one for each of the five threads, of a construction more fully described in patent to me No. 1,041,656, dated Oct. 15, 1912. 37 is a wire spring secured at one end by a set screw 38 to the angle-arm 32 at the extreme left, and at its free end positioned to bear against the four needle threads for the purpose described in 75 Osterhout Patent No. 1,134,482 dated Apr. 6, 1915, with reference to the similar spring 40 of said patent.

In operation, each thread, for example thread *a*, passes from a source of supply through its corresponding thread guide 34, thence between its spring 30 and the presser-plate 23 and through its hook 36 and under spring 37. With the sewing machine in operation and its presser-foot in engagement with the work, the spring 19 holds the bar 16 and rod 18 in the position shown in the drawings, with the pin 20 of bar 16 in contact with the end surface of plate 12, and the lug 26 seated against the flattened surface 28 of the rod 18 and the presser-plate 23 thus held up in its active position with relation to springs 30 and in which position tension is imposed upon the threads passing between said springs and plate. The tension of any spring upon its thread may be adjusted by adjustment of the corresponding screws 35 whereby the threads may be similarly or differently tensioned as desired. Lifting of the presser-foot to withdraw or introduce work thereunder actuates arm 21 to move bar 16 and rod 18 to the right against the tension of spring 19, thereby bringing the flattened surface 27 of rod 18 opposite lug 26 and permitting the plate 23 105 to swing at its lower end by gravity slightly downward (toward the right Fig. 2) sufficient to release the gripping of the threads between the springs 30 and presser-plate 23 and hence approximately simultaneously releasing the tension upon all the threads. Subsequent lowering of the presser-foot again moves the rod 18 and plate 23 to the position in which they are shown in the drawing, thereby reapplying the tension 110 (determined as to each thread by the position to which corresponding screw 35 is adjusted) upon all of the threads.

What I claim is:

1. In thread-tensioning means for sewing machines, the combination of a presser-plate or anvil member, a plurality of tension springs for directly engaging and separately pressing threads into direct contact with the surface of said anvil member to tension said threads, adjusting means for separately determining the degree of pressure to be exerted by each spring upon its thread, and means operable to effect movement of the anvil member out of and into active position 120

with relation to the tension springs to simultaneously release or impose tension upon all of the threads.

2. In thread-tensioning means for sewing machines, the combination of a pivotally supported presser plate or anvil member, a plurality of tension springs for separately pressing threads against said plate to tension said threads, adjusting means for separately determining the degree of pressure to be exerted by each spring upon its thread, and means operable to swing said presser plate on its pivot out of and into active position with relation to the tension springs to simultaneously release or impose tension upon all of the threads.

3. In thread-tensioning means for sewing machines, the combination of a pivotally supported presser plate or anvil member, a plurality of tension springs for separately pressing threads against said plate to tension said threads, adjusting means for separately determining the degree of pressure to be exerted by each spring upon its thread, and means operating automatically upon raising and lowering of the sewing machine presser foot to swing said presser plate on its pivot out of and into active position with relation to the tension springs to simultaneously release or impose tension upon all of the threads.

4. In thread-tensioning means for sewing machines, the combination of a presser plate or anvil member, a plurality of tension springs for directly engaging and separately pressing threads into direct contact with the surface of said plate to tension the threads, and means operable to move said plate into active position with relation to said tension springs and thereby apply or release tension upon all of the threads together.

5. In thread-tensioning means for sewing machines, the combination of a pivotally mounted presser plate or anvil member, a plurality of tension members for separately pressing threads against said plate to tension the threads, and means operable to move said plate on its pivot into and out of active position with relation to said tension members collectively to thereby apply or release tension upon all of the threads together.

6. In thread-tensioning means for sewing machines or the like, the combination of a presser plate or anvil member depending from a pivot having an approximately horizontal axis and over the surface of which plate a plurality of threads are adapted to pass, a plurality of tension members for separately pressing said threads against said plate to tension the threads, and means operable to swing said plate on its pivot into and out of active position with relation to said tension members and thereby apply or

release tension upon all of said threads together.

7. In thread-tensioning means for sewing machines or the like, the combination of a presser plate or anvil member depending from a pivot having an approximately horizontal axis and over the surface of which plate a plurality of threads are adapted to pass, a plurality of tension members for separately pressing said threads against said plate to tension the threads, adjusting means for separately determining the degree of pressure to be exerted by each member upon its thread, and means operable to swing said plate on its pivot into and out of active position with relation to said tension members and thereby apply or release tension upon all of said threads together.

8. In thread-tensioning means for sewing machines or the like, the combination of a presser plate or anvil member depending from a pivot having an approximately horizontal axis and over the surface of which plate a plurality of threads are adapted to pass, a plurality of tension springs for separately pressing said threads against said plate to tension the threads, adjusting means overhanging said springs and adjustable to separately determine the degree of pressure to be exerted by each spring upon its thread, and means operable to swing said plate on its pivot into and out of active position with relation to said tension springs and thereby apply or release tension upon all of said threads together.

9. In thread-tensioning means for sewing machines or the like, the combination of a presser plate or anvil member depending from a pivot having an approximately horizontal axis and over the surface of which plate a plurality of threads are adapted to pass, a plurality of tension springs for separately pressing said threads against said plate to tension the threads, adjusting screws supported to engage the springs respectively and each adjustable to determine the amount of pressure to be exerted by its spring upon its thread, and means operable to swing said plate on its pivot into and out of active position with relation to said springs and thereby apply or release tension upon all of said threads together.

10. In thread-tensioning means for sewing machines, the combination of a movably supported presser plate or anvil, a plurality of flat spring members rigidly secured to a suitable support and each having a portion adapted to directly engage and yieldingly press a thread into direct contact with the surface of said plate to tension the thread, and means operable to move said plate into and out of active position with relation to said spring members collectively to thereby apply or release tension upon all of the threads together.

11. In thread-tensioning means for sewing machines, the combination of a movably supported presser plate or anvil, a plurality of flat spring members rigidly secured to a suitable support and each having a portion adapted to directly engage and yieldingly press a thread into direct contact with the surface of said plate to tension the thread, adjusting means for separately determining the degree of pressure to be exerted by each

spring member upon its thread, and means operable to move said plate into and out of active position with relation to said spring members collectively to thereby apply or release tension upon all of the threads together. 15

In testimony whereof I have signed this specification.

ARTHUR A. MERRITT.
